UNITED STATES PATENT OFFICE

ALEXIS KELLNER, OF BERLIN, GERMANY

DESIGN FOR A COMBINED AUTOMOBILE HOOD AND RADIATOR

Application filed September 12, 1929, Serial No. 32,726, and in Germany May 13, 1929. Term of patent 14 years.

To all whom it may concern:

Be it known that I, ALEXIS KELLNER, a citizen of the German Empire, residing at Berlin, in the State of Prussia, Germany, have invented a new, original, and ornamental Design for a Combined Automobile Hood and Radiator, of which the following is a specification, reference being had to the accompanying drawing, forming a part thereof, and in which the figure is a perspective

view of a combined automobile hood and radiator showing the new design. The design of the side of the bonnet opposite that illustrated is identical with that illustrated.

I claim:—

The ornamental design for a combined automobile hood and radiator as shown and described.

ALEXIS KELLNER.
